WIRE TIGHTENING TOOL

Benedetto G. Capra, Sacramento, Calif.

Application November 9, 1942, Serial No. 465,069

1 Claim. (Cl. 81—9.3)

This invention relates to a hand tool for tightening wire, and particularly to one designed to enable a length of wire to be placed about the asbestos lagging on a pipe or the like and used as the clamping means for the lagging in place of the usual preformed band now used for the purpose, and which is not only slow to mount but tends to become loose in time if considerable vibration is present, as in locomotive service.

The principal object of this invention is to provide a tool for the purpose so arranged that a length of wire, when initially bent to a predetermined shape and placed about the lagging, may be quickly and easily tightened on the lagging so as to hold the latter in close engagement with the pipe. The tool is so arranged so that it may be manipulated, when the wire is thus tightened, to bend said wire in such a manner as to positively prevent relaxing or slipping of the tightened wire; so that when the tool is removed the wire will be maintained in the proper clamping relation on the lagging.

The tool includes a screw rod and a nut through which the rod is threaded. With continued operation the threads tend to wear out, while the remainder of the tool may remain in perfect condition.

Another object of the invention is to so mount the rod and nut that either one may be readily replaced without the necessity of discarding the entire tool, and thus lengthening the useful life of the tool considerably with but slight upkeep expense.

A further object of the invention is to provide a simple and inexpensive device and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

Figure 1 is a side elevation of the tool as in operation.

Figure 2 is a cross section on the line 2—2 of Fig. 1.

Figure 3 is a fragmentary top plan view of the tool.

Referring now more particularly to the characters of reference on the drawing, the tool includes a body of relatively long shallow C form; said body comprising a straight shank 1 of rectangular cross section, a boss 2 projecting up-

wardly from the rear end of the shank, and a nose 3 projecting upwardly from said shank at its front end. The nose tapers to a rounded forward end and is there formed with a transverse arcuate wire engaging groove 4 of circular cross section. The under side of the nose is preferably formed with a longitudinal concave slope disposed at an acute angle to the under side of the shank, while the groove 4 is disposed in a plane above the upper face of the shank.

Extending lengthwise of the shank and turnably and removably projecting through the boss 2 is a rod 5, the forward portion of which is threaded as at 6. The axis of this rod is disposed substantially in the transverse plane of the groove 4. Rearwardly of the boss the rod projects through and is removably secured, as by a pin 7, to the hub 8 of a crank handle 9, this hub serving as a shoulder engaging the boss to prevent forward movement of the rod.

The threaded portion of the rod projects through a square nut 10 of common form and wider than the shank 1. The nut is removably located in transverse slots 11 formed in a rectangular cage or yoke 12 which surrounds the shank and rod, and whose sides slidably engage the shank. The nut is thus held against rotation and must move as a unit with the cage upon rotation of the screw. The slots 11 are disposed so that the nut rides the upper surface of the shank 1, as shown in Fig. 2, thus maintaining the cage in proper guided relation on the shank. At the same time if the rod is withdrawn from the nut the latter may be readily removed from the cage by a sidewise movement, and another nut inserted. Also, if the rod threads wear out another length of threaded rod may be mounted in place by merely withdrawing the pin 7, without the necessity of replacing both the rod and handle as a unit.

The top of the cage is extended rearwardly to form a wire engaging horizontal claw 13.

In operation, a length of wire 14 of suitable nature is initially bent double so as to form a loop 15 substantially centrally of its ends and the diameter of which loop is greater than the width of the nose at its forward end so as to receive the nose therein in clearance relation, as shown in Fig. 2. The wire is then bent about the lagging 16 on a pipe 17 with the free end portions of the wire passing through the loop. The tool is then placed on the lagging, between said portions of the wire, with the under side of the nose 3 engaging the lagging and with the nose groove

engaging the loop of the wire, as shown in Fig. 1. The cage 12 is then advanced, if necessary, sufficiently to enable the free ends of the wire to extend alongside of the cage on opposite sides and to be then engaged in the claw 13 and twisted together, as at 18, to prevent relative slipping.

With the shank held in one hand the handle 9 is rotated with the other in a direction to retract the cage, so that the wire is drawn tightly about the lagging.

When the desired tightening or tension has been obtained, the tool is tipped forwardly about the forward end of the nose as an axis, as indicated in dotted lines in Fig. 1, so as to bend the adjacent portions of the free ends of the wire about the loop 15 and prevent slipping of said ends when the tool is released; the nature of the wire used being such that it remains bent of itself. The wire is then released from the tool by advancing the cage, the wire ends are cut off a short distance beyond the bends just made, and such ends are then hammered down against the lagging.

The curvature on the under side of the nose allows the wire engaging groove 4 to be quite close to the lagging, so that the wiring, even at the loop 15, is always maintained close to the lagging and a slack-forming gap of any size between the crossing parts of the wire is avoided.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention, what I claim as new and useful and desire to secure by Letters Patent is:

- 10 A wire clamping tool comprising a shank of substantially rectangular cross section, a boss projecting upwardly from the rear end of the shank, a nose projecting forwardly from the front end of the shank and provided with wire engaging means at its outer end, a wire pulling unit including a rectangular cage surrounding the shank and adapted to travel longitudinally along the same, such cage having a transverse slot formed therethrough, an interiorly threaded nut removably mounted in the slot in non-turnable relation with respect to the cage, a rod projecting through the boss on the shank and held against forward movement relative thereto, threads on the outer end of the rod engaging the threads in the nut whereby rotation of the rod in one direction or the other will advance or retract the cage, and means to rotate the rod; the outer end of the rod being free so that it may be disengaged from the threads of the nut whereby the latter may be withdrawn from the slot and another nut substituted therefor.

BENEDETTO G. CAPRA.
